LAMP

Ronald W. Froelich, 15787 Barletta Drive, Hacienda
Heights, Calif. 91745, and Jack V. Miller, 700 N.
Auburn Ave., Sierra Madre, Calif. 91024

Filed June 26, 1968, Ser. No. 12,502

Term of patent 14 years

Int. Cl. D26—02

U.S. Cl. D48—20

FIG. 1

FIG. 2

FIG. 4

FIG. 3

FIGURE 1 is a side view of a lamp showing our new design in a normal working position;

FIGURE 2 is a side view of the lamp of FIGURE 1 in a folded or stored position;

FIGURE 3 is a front view of the lamp of FIGURE 2; and,

FIGURE 4 is a side view of the lamp shown in an alternate extended position.

The dominant features of the design reside in the portion shown in full lines.

We claim:

The ornamental design for a lamp, substantially as shown and described.
